TURBINE GLAND APPARATUS

Donald J. Mosshart, Ardmore, Pa., assignor to Westinghouse Electric & Manufacturing Company, East Pittsburgh, Pa., a corporation of Pennsylvania

Application May 3, 1942, Serial No. 433,154

2 Claims. (Cl. 286—9)

The invention relates to glands for sealing a turbine casing with respect to a spindle and it has for an object to provide an apparatus of this character utilizing steam to form condensate in the clearance space of the gland and wherein one or more helical threads are employed to utilize rotary movement of the spindle to exert a pumping effect on the condensate opposed to pressure exerted thereon by steam in the casing, whereby the body of condensate accumulating in the gland clearance space and acted on by these opposed forces is effective to constitute the seal.

A more particular object of the invention is to provide a gland for a substantially vertical turbine spindle wherein steam from the turbine casing is used to form condensate and threads are provided to exert a pumping effect on the condensate opposed to the pressure exerted thereon by the steam in the turbine casing together with packing means arranged therebelow for restricting the discharge of condensate, the gland being so constructed as to provide for the drainage of water from its lower end.

These and other objects are effected by the invention as will be apparent from the following description and claims taken in accordance with the accompanying drawing, forming a part of this application, in which:

Fig. 1 is a sectional view of a turbine showing the improved gland applied thereto; and,

Fig. 2 is a fragmentary sectional view drawn to larger scale and showing the gland threads.

In the drawing, there is shown a steam turbine comprising a spindle 10 and a casing 11. The invention comprises an improved gland, at 14, carried by the casing and cooperating with the spindle to minimize leakage.

Preferably, as shown, the spindle extends substantially vertically and the gland, at 14, is carried by the lower side of the casing.

The gland, at 14, comprises a housing 16 having an inner cylindrical portion 17 cooperating with the cylindrical portion 18 of the spindle to provide a suitably small running clearance space 20.

The housing construction 16 has a jacket space 21 encompassing its cylindrical portion 17 and the jacket space is provided with inlet and outlet connections 22 and 23 providing for the circulation of cooling medium through the jacket space, the cooling medium serving to abstract heat from steam entering the clearance space 20 to produce condensation of the latter.

One or both of the cylindrical portions 17 and 18 are threaded with the thread or threads so

extending that, for the direction of rotation of the spindle 10, a pumping effect is exerted on the condensate in the running clearance space 20 in opposition to pressure exerted thereon by steam in the casing. Thus, the annular body of condensate in the running clearance space constitutes an effective seal, and any leakage from the condensate body so formed is made up by further condensation of steam.

As shown, both the cylindrical portions 17 and 18 are threaded to increase the pumping effect, the cylindrical portion 17 having an internal thread 25 and the cylindrical portion 18 having an external thread 26. Furthermore, by having threads on both cylindrical portions, not only is the pumping effect increased, but turbulence due thereto contributes to this and makes possible more effective transfer of heat to the cooling medium in the jacket. Also, heat transfer is improved because of the effect of the internal thread 25 in providing increased heat transfer surface.

Discharge of condensate from the outer or lower end of the clearance space 20 is impeded by any suitable packing 27 arranged between the housing and the spindle, the packing cooperating with the spindle and the housing to provide a space 28 for the accumulation of condensate. A leak-off connection 29 provides for discharge of drainage from the space 28. Condensate supplied from the space 28 saturates the packing 27 and thereby renders the sealing relation of the latter with respect to the spindle more effective.

Preferably, as shown, the housing structure is comprised by inner and outer tubular members 31 and 32 providing a jacket space and the inner member having the cylindrical portion 17 and there is connected to the lower end of the tubular member 31 a tubular member 33 spaced from the spindle to provide for accommodation of the packing 27. Also, a sleeve 34 is preferably carried by the spindle, the sleeve having the cylindrical portion 18 at its upper end and having its lower portion cooperating with the sleeve member 33 to define the space for the packing 27. A leak-off ring 36 cooperates with the packing at the lower side thereof.

In order to guard against the leakage of condensate along the spindle below the gland, passages are formed to provide for the leak-off of any water between the sleeve 34 and the spindle as well as water from the space at the lower side of the packing 27. Accordingly, the sleeve 34 is shown as being provided with an internal annular groove 37 connected by radial passages 38 to the

inner groove 39 formed in the ring 36, such inner groove being connected by radial passages 40 to the outer annular groove 41 formed therein. The outer annular groove cooperates with the interior surface of the sleeve member 33 to form an annular chamber connected by ports 42 with the annular space 43 in communication with the leak-off connection 29.

Thus, it will be seen that the packing 27 resists the escape of condensate from the lower or outer end of the clearance space, that is, due to the packing, the pressure difference between the interior of the turbine casing and the space 28 is substantially reduced, thereby reducing the pressure effective to produce flow outwardly through the clearance space and making it easier for the threads effectively to exert the necessary opposing pumping action. Any leakage from the gland construction occurs through the leak-off connection 29, the grooves and passages formed in the sleeve 34, the ring 36 and in the sleeve member 33 providing for drainage of all spaces to the leak-off connection 29.

While the invention has been shown in but one form, it will be obvious to those skilled in the art that it is not so limited, but is susceptible of various changes and modifications without departing from the spirit thereof, and it is desired, therefore, that only such limitations shall be placed thereupon as are specifically set forth in the appended claims.

What is claimed is:

1. In a gland for sealing a substantially vertical turbine spindle with respect to the casing, a housing carried by the casing at the lower side thereof and encompassing the spindle; a sleeve carried by the shaft and arranged within the housing; said housing and sleeve having closely spaced cylindrical portions defining small running clearance communicating at its upper end with the interior of the turbine casing; said housing having an annular jacket space encompassing its cylindrical portion; means providing for the circulation of cooling medium through the jacket space to effect condensation of steam entering the running clearance space from the casing; internal and external threads carried by the cylindrical portions, bounding the running clearance space, and extending so that, for the

direction of rotation of the rotor, they exert a pumping action on the condensate in the clearance space opposed to pressure exerted thereon by steam in the casing; means opposing the discharge of condensate from the outer end of the running clearance space comprising packing cooperating with the housing and with the sleeve; a ring cooperating with the packing at the lower end thereof; and means including passages formed in the lower end portion of the sleeve, in the ring, and in the housing and providing for the leak-off of condensate from the space between the sleeve and the spindle and from the packing.

15 2. In a gland for sealing a turbine spindle with respect to its casing, a sleeve construction carried by the casing and encompassing the spindle; said sleeve construction including a first member having one end exposed to the interior of the 20 casing and a second member extending outwardly from the first member; said first member and the spindle having closely spaced cylindrical portions defining an annular condensing clearance space communicating at one end with the 25 interior of the casing; means cooperating with the first member to provide an annular jacket space encompassing said cylindrical portion thereof; means providing for the circulation of cooling medium through the jacket space to effect condensation of steam entering the clearance space from the interior of the casing; a thread on at least one of said cylindrical portions and extending so that, for the direction of 30 rotation of the rotor, it exerts a pumping action 35 on the condensate in the clearance space to oppose the pressure exerted thereon by steam in the casing; said second member cooperating with the spindle to provide an annular packing space in communication with the other end of 40 said clearance space; packing in said annular space and having sealing relation with respect to the spindle, the sleeve construction, the spindle, and the casing being constructed and 45 arranged to provide a leak-off space for condensate escaping from the packing; and a leak-off connection carried by the casing and communicating with the leak-off space.

DONALD J. MOSSHART.
